UNITED STATES PATENT OFFICE.

ALONZO SEDGWICK AND WILLIAM WOMERSLEY, OF POUGHKEEPSIE, AND RALPH J. BROWN, OF NEW YORK, ASSIGNEES, BY MESNE ASSIGNMENTS, TO D. H. BURRELL & COMPANY, OF LITTLE FALLS, NEW YORK.

PAPER-FEEDER.

SPECIFICATION forming part of Letters Patent No. 391,087, dated October 16, 1888.

Application filed June 9, 1887. Serial No. 240,727. (No model.)

To all whom it may concern:

Be it known that we, ALONZO SEDGWICK and WILLIAM WOMERSLEY, both of the city of Poughkeepsie, in the county of Dutchess and State of New York, and RALPH J. BROWN, of the city, county, and State of New York, have invented a new and useful Improvement in Paper-Feeders, of which the following is a specification.

10 This invention relates to that class of paper-feeders by which sheets are successively fed from a pile to a printing-press, ruling-machine, or other machine in which the sheets are operated upon.

15 The object of this invention is to provide means by which the sheets are placed in correct register laterally, which is of great importance, especially when feeding to a printing-press.

20 Heretofore it has been very difficult to feed sheets to printing-presses by automatic feeders in such manner that the printing on both sides of the sheet would be in correct register back to back, and a large percentage of waste 25 was occasioned by the incorrect register of the sheets.

The object of our invention is to overcome these difficulties; and it consists of the improvements which will be hereinafter fully described, and pointed out in the claims.

In the accompanying drawings, consisting of two sheets, Figure 1 is a vertical section of a paper-feeder provided with our improvements, the section being taken in the direction 35 of the feed movement. Fig. 2 is a longitudinal section, on an enlarged scale, of one of the side fingers and connecting parts. Fig. 3 is a top plan view thereof. Figs. 4 and 5 are cross-sections in lines x x and y y , Fig. 2. Fig. 6 is 40 a sectional elevation showing the side finger raised preparatory to grasping the sheet. Fig. 7 is a longitudinal section of the side guide with which the side finger is connected. Fig. 8 is a bottom plan view of the mechanism by which 45 the side fingers on both sides of the feed-board are connected.

Like letters of reference refer to like parts in the several figures.

A represents the main feed-board, which

may be the feed-board of a printing-press to 50 which the paper is fed, as indicated in the drawings.

a represents the cylinder of a printing-press to which the sheets are fed, and a' represents one of the usual front guides with which the 55 press is provided and against which the sheets are fed.

B represents an auxiliary feed-board placed upon the lower portion of the main feed-board A ; and b represents the lower feed-tapes, 60 whereby the sheets are carried upon the auxiliary feed-board B , the lower tape-roller, b' , being preferably so arranged that the upper edge of the sheet has cleared the lower tapes when the lower edge rests against the front 65 guides, a' .

b' represents the upper feed-tapes, which may be of any suitable construction.

The sheets are fed successively from a pile upon the auxiliary feed-board B by any suitable automatic feeding mechanism. The construction of such feeding mechanism forms no part of this invention, and it may be of any suitable kind—for instance, that described and shown in an application for patent filed by 75 A. Sedgwick, October 23, 1886, Serial No. 217,004.

C represents a laterally-movable clamping-finger arranged on the auxiliary feed-board B so as to seize each sheet near its lateral edge 80 and move it laterally on the feed-board to the point of register. The finger C has the form of an elbow-lever, and is composed of an upper arm, c , standing horizontally, or nearly so, in its normal position, and a depending arm, 85 c' . The finger is pivoted at the junction of its two arms by a horizontal bolt, d , to two ears, d' , between which the finger is arranged, and which are formed on the upper side of a slide, D . The long arm c of the finger C is provided 90 near its end with a head, c'' , of rubber, leather, or other suitable material, which will enable the finger to take a firm hold on the paper.

E represents upright side guides secured to the slide D on both sides of the long arm c 95 of the finger C and forming a rest or stop for the lateral edge of the sheet.

e e' represent curved guides, which are se-

cured to the inner sides of the side guides, E E', and which project inwardly and upwardly therefrom, so as to guide the lateral edges of the sheets downwardly against the side guides 5 at their point of junction with the slide D. The curved guide e is provided with an upward extension, e², which assists in guiding the sheets under the finger C. The depending arm c' of the finger C projects downwardly 10 through an opening, f, in the slide D, which opening limits the oscillating movement of the finger on its pivot. The arm c' is bifurcated below the slide D and straddles a sleeve, G, which is adjustably secured to a horizontal 15 rod, g, arranged on the under side of the auxiliary feed-board B and guided in bearings g¹ g², attached to the same. The sleeve G is provided with collars g³ g⁴, between which the bifurcated arm c' is arranged.

20 H represents a slotted guide-plate on which the slide D moves inwardly and outwardly, and which is arranged transversely on the feed-board. This plate H is in turn supported on a slotted plate, I, which is secured in an opening, i, formed in the auxiliary feed-board near the side thereof. The guide-plate H is secured to the plate I by screws h or other means, which permit the plate H to be adjusted on the plate I inwardly and outwardly, as may be 25 required, to place the plate H in the proper position for registering the sheets. The slide D is held in place on the slotted plate H by a transverse spring, j, which is secured to a stud, j', on the under side of the slide, and which 30 bears against the under side of the plate H, as represented in Fig. 4.

The upper surfaces of the slide D and the plates I and H are flush with the upper surface of the auxiliary feed-board, so that the 40 sheets can pass freely over these parts, the plate H forming a recessed way in the feed-board, in which the slide D moves.

By locating the actuating mechanism underneath the slides to which the clamping-fingers are attached the space above the feed-board is not obstructed between the clamping-fingers, and the upper carrying-tapes can be readily extended to the extremity of the feed-board.

50 A clamp-finger, C, is required on one side of the feed-board only; but in order to enable the sheets to be registered against either side of the feed-board, as circumstances may require, provision is made for operating the clamping-finger on either side of the board. To this end an actuating-rod, k, is arranged on the opposite side of the feed-board in line with the rod g, and the feed-board is provided adjacent to the rod k with an opening, k', supporting-plate k², slotted plate k³, sleeve k⁴, and a clamping-finger corresponding with the similar parts on the opposite side of the feed-board. The rods g and k are connected by a lever, l, and rods l' l² and an arm, l³, as represented in Fig. 8. The arm l³ is secured to the rod k and a parallel rod, m, which slides in bearings m' m², and is provided with a spring,

n, resting against the bearing m', and a collar, n', on the rod m. This spring tends to hold the rods g and k in their innermost position.

o represents a pulley attached to the under side of the auxiliary feed-board B, and o' is a cord or chain running around said pulley and attached with one end to the rod m and with 75 its other end to a rod, p, which extends upwardly over the main feed-board and connects with the lower arm, p', of an elbow-lever, P, the upper arm, p², of which rests upon a cam, Q. The latter is secured to a horizontal shaft, q, which makes one revolution for every sheet of paper which is fed forward. This cam is provided with a deep depression, r, a raised projection, r', in rear of the deep depression, and a concentric face, r², extending around the greater part of the cam, 80 slightly below the projection r'.

When the lever P rests upon the projection r' of the cam Q, the rods g and k are in their outermost positions, and the clamping-finger C, connected with either of said rods, stands in its outermost position. This position of the clamping-finger and of the slide D, to which it is attached, determines the outermost position of the side guides, E E', secured to the 95 slide D. The outermost position of these side guides is the point to which the lateral edge of the sheet is required to be moved in order to bring it in correct lateral register; hence, in adjusting the slotted plate H on its supporting-plate I and the collar G on the rod g these parts are so adjusted that when the slide D is in its outermost position the side guides, E, coincide with the line on which the lateral edges of the sheets must be placed in order to 100 be in correct register. The cam revolves in the direction of the arrow in Fig. 1. When the lever P drops into the deep recess r of the cam, the rod g moves quickly inward under the pressure of the spring n and carries the slide D with it, the finger C being elevated, as represented in Fig. 6, and moving the slide by contact of its lower arm, c², against the inner end of the opening f. The extent of this inward movement of the slide is such as to 110 bring the lateral edges of the sheets in contact with the side guides, E E', under the usual variations with which the sheets pass over the feed-board.

In Fig. 7 s s' s² represent three different 115 positions of sheets passing over the feed-board, in each of which the side guides, E E', strike the lateral edge of the sheet before the side guides reach the inner limit of this movement, which is indicated by dotted lines. 120 As soon as the side guides strike the edge of the sheet the latter is pushed back by the side guides until the side guides reach the inner limit of their movement. The lever P now rises out of the deep recess r and draws the rod g rapidly outward, thereby compressing the 125 spring n. The first part of the outward movement of the rod g causes the finger C to be turned on its pivot, so as to bring the head c² 130

down on the sheet, which latter is thus firmly clamped between the finger C and the slide D, the edge of the sheet resting against the side guides, E E'. When the finger has clamped 5 the sheet, the continued outward movement of the rod *g* causes the slide D to be moved outwardly until the outer limit of the movement is reached, which is the case when the lever P rests against the projection *r'* of the cam Q. 10 Immediately after the slide has reached this position the lever P drops upon the concentric face *r*² of the cam, which permits the rod *g* to move inwardly under the pressure of the spring far enough to raise the finger from the 15 sheet without disturbing the position of the slide D. The sheet so released is seized by the nippers of the press and drawn away. The lever P now rests upon the concentric face *r*² of the cam Q, and holds the slide in its outer- 20 most position until the next inward movement takes place.

The clamping-finger which is not required for use can be removed with its supporting-slide from the feed-board. By this means each 25 sheet is firmly seized and brought to the same line laterally, thereby insuring a correct side register of the sheets and enabling the sheets to be fed with certainty to a printing-press or other machine which requires a correct register of the sheets.

We claim as our invention—

1. The combination, with the feed-board, of a transversely-moving slide, a clamping-finger pivoted to said slide, and an actuating-rod 35 connected with the clamping-finger, whereby the slide is moved by the actuating-rod through the medium of the clamping-finger, substantially as set forth.

2. The combination, with the feed-board, of 40 a laterally-moving slide, a clamping-finger pivoted to said slide, a stop formed on said

slide whereby the lifting movement of the clamping-finger is limited, and a transversely-moving actuating-rod connected with said finger, whereby the finger is lifted from the paper before the slide is moved inwardly by said actuating-rod, substantially as set forth. 45

3. The combination, with the feed-board having a slotted plate, H, of a slide, D, provided with side guides, E E', a finger, C, pivoted to said slide, and an actuating-rod, *g*, provided with a sleeve, G, which engages said finger, substantially as set forth. 50

4. The combination, with the slide D, of the side guides, E E', curved guides *e e'*, secured to the inner sides of the guides E E', and the pivoted clamping-finger C, substantially as set forth. 55

5. The combination, with the slotted plate H, of the slide D, bearing against one side of said plate, and a spring, *j*, attached to said slide and bearing against the opposite side of said plate, and a clamping-finger, C, mounted on said slide, substantially as set forth. 60

6. The combination, with the actuating-rod 65 *g* and *k*, arranged at opposite sides of the feed-board, of the lever *l*, connecting-rods *l' l'*, arms *t*, rod *m*, spring *n*, cam Q, and mechanism connecting said cam with the rod *m*, substantially as set forth. 70

7. The combination, with the slide D, and a clamping-finger, C, attached thereto, of a slotted plate, H, on which the slide moves, and a supporting-plate, I, to which the plate H is adjustably attached, substantially as set forth. 75

Witness our hands this 2d day of June, 1887.
